DETACHABLE CLASP

Ferdinand R. Eichner, Pontiac, Mich.

Application February 28, 1942, Serial No. 432,751

10 Claims.

(Cl. 24—85)

The present invention relates to detachable clasps, and more particularly to a clasp for attaching an identification badge to a garment.

The primary object of the invention is to provide a resilient clasp to which an identification badge may be secured, to facilitate easy manipulation of the badge and to prevent the tearing and damaging of the cloth of a garment to which the badge is attached.

Another object of the invention is to provide a resilient clasp having mutually depressed rib portions to frictionally engage the fabric of the garment and prevent loss or detachment of the badge and clasp through accidental removal from the garment.

Another object of the invention is to provide a clasp of the above type having aligned apertures for the reception of the badge pin fastener, so that the pin fastener will not contact the garment on which the badge is placed, eliminating injury to the wearer through sticking and damage to the garment by the pin fastener point tearing the threads of the garment.

Another object of the invention is to provide a detachable clasp for supporting an identification badge wherein the badge may be locked in place and prevented from becoming lost or detached from the clasp.

Another object of the invention is to provide a clasp of the above mentioned character which is formed of a transparent material such as synthetic condensation products of the resinous and vinyl type so that the clasp may be applied to various colored garments without noticeable distinction and without presenting an unpleasing appearance.

Another object of the invention is to provide a clasp adapted to support an identification badge which may be formed of a material suitably colored to correspond to the color of the garment to which the clasp is attached, thereby presenting a pleasing appearance to the esthetic eye.

In the drawing:

Figure 1 is a side elevation partly in section illustrating a preferred embodiment of the invention;

Fig. 2 is a front elevation of the same showing the aligned openings for receiving the identification badge pin fastener.

Fig. 3 is a side elevation similar to Figure 1 illustrating the manner in which an identification badge is attached thereto.

Fig. 4 is a rear elevation showing the rear jaw member of the clasp and the position of the iden-

tification badge extending substantially the entire overall area thereof.

Fig. 5 is a front elevation illustrating the clasp and showing the identification badge attached to the aligned openings of the mutually corrugated rib portion.

Fig. 6 is a horizontal cross sectional view taken on line 6—6 of Fig. 3 looking in the direction of the arrows showing the identification badge pin fastener lock preventing device blocked by one jaw of the clasp.

Fig. 7 is a side elevation of a modified form of the invention illustrating a different support for receiving the pin fastener of the identification badge.

Fig. 8 is a front elevation of the modified form shown in Fig. 7 more clearly illustrating the location of the support and its relation with respect to the clasp member, and

Fig. 9 is a perspective view of a clasp embodying the invention showing an identification badge secured thereon and illustrating the manner in which the clasp is attached to a garment.

In general, the invention comprises a resilient transparent clasp member adapted to be positioned on a garment having mutually transverse corrugated portions or rib-like extensions so that one set of corrugations can be apertured for receiving the pin fastener of an identification badge and so that both corrugated portions may coact to maintain the clasp in position on the garment without resorting to the use of the pin fastener and eliminating to a large degree damage to the cloth of the garment and the prevention of numerous pin hole openings as in the case where the pin fastener is employed and depended upon solely for securing the identification badge to a garment.

Further, the invention consists in providing an attractive support for an identification badge which may be formed of various-colored phenolin condensation products to enhance the beauty of the devices and to render the same less conspicuous when the badge is attached to the clasp and the clasp fixed or secured to a garment of a corresponding color.

It is intended to produce the clasps in transparent materials as well as colored materials so that they may be purchased to blend with a particular colored garment and individuality may thus be set up by selecting a number of variously colored clasps to suit the particular desire.

In the drawing, attention is first directed to Figures 1 to 6 and 9 inclusive wherein there is

shown a preferred embodiment of the invention and wherein the reference character 10 will be employed to generally designate a clasp having parallel jaw portions 11 and 12 formed from a strip of resilient material bent upon itself as shown at 13 to provide a relatively large loop portion. The free ends of the jaw portions are outwardly bent as at 14 and 15 respectively so that the jaw portions may separate when the clasp is applied to a garment, handkerchief pocket or other portion of the garment.

The jaw portion 11 of the clasp is formed with two or more transversely arranged depressions or corrugations 16 and 17 connected by an arcuately curved portion 18 thereby providing a sinusoid shaped jaw member and providing projecting friction increasing ribs 19 and 20.

Said ribs 19 and 20 are so adapted to coact with mutually presented transverse depressed portions 21 and 22 formed on the jaw portion 12 complementary with the ribs 19 and 20 and arranged so that the jaw portions may cooperate to be clamped on a garment or other piece of wearing apparel and prevented from slipping therefrom.

The depressions or corrugations 21 and 22 provide outwardly projecting transverse ribs 23 and 24 which are in substantially the same plane so that they may be connected by an arcuately curved portion 25 complementary with the arcuately curved connecting portion 18. Further, said transverse ribs 23 and 24 provide a contact support for an identification badge to prevent wobbling and vibration when the badge and clasp are in position.

Each of the ribs 23 and 24 are provided with transversely aligned apertures 26 and 27 respectively which are formed intermediate the ends of the ribs and a considerable distance from the vertical edges of the jaw portion 11. The apertures are formed as close to the bottom walls of the transverse depressions as possible to prevent the material of the garment from being pinched therein.

In Figs. 3, 4, 5 and 6, there is shown a conventional form of identification badge generally consisting of a casing frame 28 having its marginal oval shaped edge 29 bent upon itself to provide a flange for holding a backing member 30 in position. A window 31 is formed in the upper portion of the frame for displaying a photograph of the person identified while a window opening 32 is formed in the lower portion of the frame for further identification data.

Identification badges of this character are generally provided with fastening means such as is shown in the drawing including a pin fastener bar 33 pivotally attached to the backing member 30 or at 34 to a bifurcated lug soldered or otherwise secured thereto. The opposite swinging end of the pin fastener bar 33 is adapted to be held in place by a loss preventing device, comprising a pair of spaced lugs 35 having annular openings communicating with slots 36 for the entrance and escape of the end of the pin portion bar. The circular openings in the lugs 35 rotatably receive a keeper 37 which is interposed between the lugs and is provided with a suitable slot 38 adapted to align with the slot 36 during the entrance and escape of the pin fastener end. Formed on the keeper 37 is a pair of radial projections 39 to facilitate rotation of the keeper and thus lock the pin fastener in position.

When the identification tag 28 is secured to the clasp 10 by passing the pin fastener 33

through the apertures 26 and 27 the keeper as shown in Figures 3 and 6 will be held against rotation by reason of the fact that the projections 39 engage the front wall of the clasp portion and prevent the escape of the pin fastener when the badge is in position.

By employing a slender, blunt instrument, the projection 39 may be forced in a direction to align the slots 36 and 38 for either removing or positioning the badge on the clasp. When the badge has thus been positioned on a clasp of the desired color, the assembly may be clipped or attached to the pocket P of a suit or other garment S as shown in Fig. 9 so that the return bent portion 13 fits well down on the edge of the pocket. It will readily be observed that the clasp may be suitably colored to coincide with the color of the garment, in which instance, the clasp will be unnoticeable and inconspicuous and the badge will be exposed for the purpose of proper identification.

In Figures 7 and 8, the clasp 10a is similar in form to the invention depicted in Figures 1 to 6 and 9 inclusive and includes oppositely disposed jaw portions 11a and 12a formed from a strip of flexible material return bent as at 13a.

The jaw portions 11a and 12a are provided with similar extending free end portions 14a and 15a and is provided with mutual depressions 16a and 17a connected by an arcuate portion 18a thus providing transversely extending ribs 19a and 20a. The opposed jaw portion 12a is complementarily depressed transversely as at 21a and 22a providing a fabric gripping and anti-slipping surface between the jaw portions.

The transversely depressed portions 21a and 22a form spaced projecting ribs 23a and 24a to which is attached a tubular support 26a, having a central bore 27a for receiving the pin fastener bar of a badge in a manner similar to that shown in Figures 1 to 6 and 9 inclusive.

It is to be noted, that the tubular support 26a is in the same relative position with the axis of its bore coinciding with the apertures 26 in Figures 1 to 6 and 9 inclusive by reducing the size of the depressions 21a and 22a so that the pin fastener bar will lie in the same relative position and cause the projections 39 on the badge keeper to engage the lower end of the pin portion 13a.

The clasp of both forms of the invention may be produced by a simple stamping operation or may be formed of an extended plastic material possessing sufficient resilient characteristics such as a phenolic condensation product or vinyl acetate derivative.

It is to be understood that the forms of the invention herewith shown and described are to be taken as preferred embodiments of the invention and that various changes in the shape, size and arrangement of parts may be resorted to without departing from the spirit of the invention or the scope of the appended claims.

What I claim is:

1. A badge supporting clasp for receiving the pin fastener thereof and adapted to be frictionally retained on an article of wearing apparel comprising a U-shaped resilient clamping member of substantially the same dimensions as the badge, mutually defined closely spaced transversely extending corrugations formed in the jaws of said clamping member intermediate their length and means carried by one of said jaws transversely of said corrugations for supporting 5 a badge said means providing a relatively rigid

connection between the clasp and badge at the spaced apart corrugations.

2. A badge supporting clasp for receiving the pin fastener thereof and adapted to be frictionally retained on an article of wearing apparel, comprising a U-shaped resilient clamping member of substantially the same dimensions as the badge, transversely arranged mutually defined corrugations formed in the jaws of said member in slightly spaced apart relation and means carried by one of said jaws extending longitudinally thereof and transversely of the corrugations for detachably supporting a badge said means providing a relatively rigid connection between the clasp and badge at the spaced apart corrugations.

3. A badge supporting clasp for receiving the pin fastener thereof and adapted to be frictionally retained on an article of wearing apparel, comprising a U-shaped clamping member formed of resilient transparent material, mutually defined transversely arranged slightly spaced corrugations formed in the jaws of the clamping member and means carried by one of said jaws extending longitudinally thereof and transversely of the corrugations for supporting a badge said means providing a relatively rigid connection for the badge between the humps of the slightly spaced corrugations.

4. An identification badge supporting clasp for receiving the pin fastener of a badge, comprising a transparent resilient U-shaped clamping member of substantially the same width as the badge, transversely formed spaced apart corrugations formed in the jaws of said clamping member, said corrugations defining complementary gripping portions for frictionally engaging and being retained on an article of wearing apparel and means on the corrugations of one of the jaws extending longitudinally thereof and transversely of the corrugations to support the identification badge said means providing a relatively rigid connection for said badge with the pin fastener thereof bridging the spaced apart corrugations.

5. An identification badge supporting clasp, comprising a transparent resilient U-shaped clamping member of substantially the same size and dimensions as the badge, transversely extending mutually arranged slightly spaced apart corrugations formed on said jaw portions of the clamping member and means on one set of corrugations extending longitudinally of the jaw and transversely of the corrugations for detachably supporting said identification badge said means providing anchoring points for the badge at spaced apart locations whereby twisting or turning of said badge will be prevented.

6. A badge supporting clasp adapted to receive the pin fastener of a badge comprising a U-shaped strip of material of substantially the same size and dimensions as the badge, corrugations formed in one leg of the U-shaped strip in slightly spaced apart relation and said corrugations on one of the legs of the U-shaped strip being provided with aligned apertures extending longitudinally of the jaw and transversely of the corrugations for receiving the pin fastener mem-

ber of the badge whereby said badge will be rigidly connected to the clasp and supported at the spaced apart corrugations against relative turning movement.

5 7. A badge supporting clasp adapted to be frictionally attached to an article of wearing apparel for receiving the pin fastener of a badge, comprising a U-shaped transparent strip of material of substantially the same size and dimensions as the badge, slightly spaced apart transversely arranged corrugations formed in one leg of the U-shaped strip and said corrugations having a pair of aligned apertures extending longitudinally of the jaw and transversely of the corrugations for receiving the pin fastener of said badge said apertures being formed on the hump portions of the spaced apart corrugations to provide multiple attaching points for the badge pin fastener.

20 8. A badge supporting clasp adapted to be frictionally attached to an article of wearing apparel for receiving the pin fastener of a badge, comprising a U-shaped clamping member of increased width and of substantially the same dimensions as the badge, complementary slightly spaced apart corrugations formed in the legs of the U-shaped clamping member, said clamping member having one of its clamping legs slightly enlarged and provided with apertures formed through the humps of the corrugations therein extending longitudinally of the jaw and transversely of the corrugations for receiving the pin fastener of said badge whereby the pin fastener of the badge will be supported at spaced apart locations to prevent relative turning movement thereof.

25 9. A badge supporting clasp adapted to be frictionally attached to an article of wearing apparel for receiving the pin fastener of a badge, comprising a U-shaped clamping member of substantially the same size and dimensions as the badge, transversely formed slightly spaced apart complementary corrugations in the clamping member, and one set of said corrugations being of increased size and having spaced apertures aligned longitudinally of said jaw and transversely of said corrugations for receiving the pin fasteners of said badge said apertures being formed on the hump portions of the spaced apart corrugations to provide multiple attaching points for the badge pin fastener.

30 40 45 50 55 60 65 10. An identification badge supporting clasp adapted to be frictionally attached to an article of wearing apparel for receiving the pin fastener of a badge, comprising a U-shaped clamping member of substantially the same size and dimensions as the badge, closely spaced apart complementary corrugated gripping portions formed on the clamping member and a tubular support attached to one set of said corrugations extending transversely thereof and longitudinally with respect to said clamping member for receiving the pin fastener of said badge said tubular support being adapted to receive the pin fastener of a badge and support the same between the anchoring points of the humps of the spaced corrugations.

FERDINAND R. EICHNER.
